SPRING STRUCTURE

Filed Dec. 31, 1929

Inventor:
Fred R. Zimmerman
By Walter M. Fuller Atty

UNITED STATES PATENT OFFICE

FRED R. ZIMMERMAN, OF CHICAGO, ILLINOIS, ASSIGNOR TO BURTON-DIXIE CORPORATION, OF CHICAGO, ILLINOIS, A CORPORATION OF ILLINOIS

SPRING STRUCTURE

Application filed December 31, 1929. Serial No. 417,669.

This invention pertains to cushion or spring structures employing upright, coiled springs and concerns more particularly novel and serviceable means for tying or connecting them together to form what may be termed a spring assembly adapted for advantageous use in cushions, mattresses, bed-springs and similar constructions.

One aim of the invention is to so crimp or bend the end coils or terminal rings of the springs and the tie-wires preliminarily or initially, that they may be easily and readily sprung into permanent, effective, interlocking engagement without additional bending, thus rendering the assembling operation unusually simple, the united coils and wires being rigidly secured together in their connected relation.

In the associated drawings, one desirable embodiment of the invention, by way of example only, has been presented for use in connection with the following detailed description, and, for ease in understanding the construction, like reference numerals have been employed to designate the same parts throughout the various views.

In these drawings:—

Figure 1 is a fragmentary, top, plan view of the improved and novel spring-assembly; 20 Figure 2 is a vertical section on line 2—2 of Figure 1; and

Figure 3 is a fragmentary, top, plan view and Figure 4 is an edge view of the top coil of one of the springs and the companion tie-wire, showing their approximate relation to one another just preliminary to being sprung into permanent interlocking association.

Referring to these drawings, it will be seen that the spring-cushion structure includes a plurality of rows of erect, hour-glass or double-tapered, coiled springs 11, 11, those of adjacent or proximate rows being in staggered or offset relation, as is more or less common practice.

The top coils of such springs are connected or joined together in the new fashion rendered possible by my invention and the bottom convolutions or rings of the springs are united or tied together in like manner, so

that a description of the former will suffice for both.

Each of such end-coils or terminal-rings 12 of the springs is crimped or bent at diametrically-opposite points, so that zigzag tie 55 or securing wires 13, 13 may be properly and adequately fastened thereto to link or bind them together, each of such tie-wires being connected in sequence to adjacent springs of the same row with intermediate similar 60 unions with the springs of the next row.

At each such location, the wire of the end-ring is bent inwardly at 14, then outwardly at 15, then inwardly again at 16, and outwardly at 17, forming two, spaced, inwardly-extended 65 projections 18 with an intermediate or middle, outward extension 19.

Each wavy or serpentine connecting-wire 13, at each of its points of attachment to a spring end-coil, is bent to provide a downwardly-extended member 21 and an immediately-adjacent upwardly-arranged portion 22 unitedly forming a trough 23 designed to receive the part 14 of the companion end-ring, the wire 13 also having similar parts 24 and 25 forming another channel 26 for the accommodation of the portion 17 of the end-coil.

As is fully shown, the portions 22 and 25 of the tie-wire are joined together by a straight or horizontal section 27 which, in the united 80 construction, overlies the projection 19 of the end-coil to securely fasten the parts together.

As has been suggested above, the spring end-ring formations and the tie-wire bendings as shown and described are completely 85 formed before the elements are assembled, the latter operation being performed without additional or supplemental bending by merely springing the two parts into the interlocked association portrayed in Figure 1.

To accomplish this result, the tie-wire is applied to the end-coil in substantially the manner shown in Figures 3 and 4 with the lock-bar 27 of the wire below its cooperating lug 19 of the terminal coil of the spring, and then, by slightly twisting the two parts, they may be sprung temporarily or momentarily sufficiently to permanently position the portion 27 over the part 19, the companion sec- 90 95 100

tions of the two parts snapping readily into their final interlocked relationship.

The spring-assembly constructed according to the principles of this invention may be manufactured at relatively small cost and the elements entering into the construction are firmly and securely fastened together for the efficient performance of their serviceable functions.

10 Those acquainted with this art will understand that many changes may be made in the structure and still fall within the scope of the invention, as defined by the appended claims, for example, the tie-wires, instead of 15 extending above the end-coils of the springs and with the parts 27 above the sections 19, may project below such terminal-rings and have the portions 27 similarly under the parts 19.

20 Other changes may be incorporated in the construction and still retain the structural characteristics and functional advantages of the invention.

I claim:—

25 1. In a spring-structure, the combination of a plurality of upright coiled springs in rows in staggered relation, each of such springs having an end-ring which at each of two of its opposite sides is bent sidewise inwardly of said end-ring at spaced points and outwardly between such points to provide an intermediate outstanding projection, and tie-wires connected to and interlocked with said opposite sides of each end-ring of said springs, each such wire being connected successively to the end-rings of springs of adjacent rows, each such tie-wire at each such connection being bent to extend across the end-ring at two points, across said first two sidewise bent portions on the side thereof opposite its extension across the ring, and across said intermediate projection on the same side that the tie-wire extends across said ring, said end-rings and wires being initially fully bent to firmly and finally spring together into the specified interlocking relation.

30 2. In a spring-structure, the combination of a plurality of upright coiled springs in rows in staggered relation, each of such springs having an end-ring which at each of two of its opposite sides is bent sidewise inwardly of said end-ring at spaced points and outwardly between such points to provide an intermediate outstanding projection, and tie-wires connected to and interlocked with said opposite sides of each end-ring of said springs, each such wire being connected successively to the end-rings of springs of adjacent rows, each such tie-wire at each such connection being bent to extend across the end-ring at two points, across said first two sidewise bent portions on the side thereof opposite its extension across the ring, and across said intermediate projection on the same side that the tie-wire extends across

said ring, said end-rings and wires being initially fully bent to firmly and finally spring together into the specified interlocking relation, said tie-wires constituting the sole means securing said spring end-rings 70 together.

3. In a spring-structure, the combination of a plurality of upright coiled springs in rows in staggered relation, each of such springs having an end-ring which at each of two of its opposite sides is bent sidewise inwardly of said end-ring at spaced points and outwardly between such points to provide an intermediate outstanding projection, and tie-wires connected to and interlocked with said opposite sides of each end-ring of said springs, each such wire being connected successively to the end-rings of springs of adjacent rows, each such tie-wire at each such connection being bent to extend over the end-ring, beneath said spaced inwardly extended parts thereof, and over said projection, said end-rings and wires being initially fully bent to firmly and finally spring together into the specified interlocking relation, said tie-wires 80 constituting the sole means securing said spring end-rings together.

In witness whereof I have hereunto set my hand.

FRED R. ZIMMERMAN. 95
